UNITED STATES PATENT OFFICE.

FRED B. BALDWIN, OF MUSKEGON, MICHIGAN, ASSIGNOR OF ONE-HALF TO
HENRY L. YOUNG, OF CHICAGO, ILLINOIS.

DESIGN FOR A SHOW-CASE.

SPECIFICATION forming part of Design No. 21,763, dated August 9, 1892.

Application filed June 25, 1892. Serial No. 438,049. Term of patent 14 years.

To all whom it may concern:

Be it known that I, FRED B. BALDWIN, a citizen of the United States, residing at Muskegon, in the county of Muskegon and State of Michigan, have invented and produced a new and original Design for a Show-Case; and I do hereby declare the following to be a full, clear, and exact description of the invention, such as will enable others skilled in the art to 10 which it appertains to make and use the same.

This invention has reference to a new and original design for a show-case, the object being to ornament and embellish the appearance of a case used for displaying therein 15 goods of various kinds; and it consists in a new design for the case, substantially as herein shown and described.

In the annexed drawings, illustrating my design, Figure 1 is a side elevation of a show-case, showing the design. Fig. 2 is a horizontal sectional plan view of the same on the line *x x* of Fig. 1.

Like letters of reference designate like parts in both figures.

25 A denotes the main upper rectangular portion of the design, which is of suitable size, and is surmounted by the horizontal ornamental edge *a*, and is mounted upon an orna-

mental base B. In the front of the part A is the representation of a door C. The case A is 30 illustrated as being transparent, a series of horizontal shelves *b b* being observed therethrough. Below the base-plate B is a skeleton framework forming the ornamental lower portion of my design and consisting of the 35 ornamental uprights D D, of which there are four, and which are situated between the base-plate B and the lower base-plate E. Projecting upward from the part E at the central portion thereof is an ornamental post F. 40 Running from the post F to each of the embellished uprights D is an inclined rib G, the lower end of which meets the post F and the base E, while the upper end meets the uprights D at about midway of its height, said 45 end of rib G being provided with a rounded knob or projection *g*.

What I claim is—

The design for a show-case, substantially as herein described and shown. 50

In testimony whereof I affix my signature in presence of two witnesses.

FRED B. BALDWIN.
